UNITED STATES PATENT OFFICE

2,450,613

MECHANICAL POOL TABLE

Felix Radinsky, Olympia, Wash.

Application July 19, 1944, Serial No. 545,583

2 Claims. (Cl. 273—11)

1

This invention relates generally to game tables or like devices and more particularly to a mechanical pool table by means of which the well-known game of pool may be simulated in many of the various aspects thereof and in which considerable skill may be exercised by the operator of the device in selectively performing a plurality of different direct pocket shots or a plurality of combinations of bank or cushion-to-pocket shots thereon, thus affording amusement, entertainment, and tests of skill to those who operate the device.

According to the invention, a coin controlled means is provided for releasing a predetermined number of balls for each coin deposited in the device whereby a plurality of persons equal in number to the number of balls released may play the game on one coin, each ball after being played being returned either by way of one of the pockets or by way of a gate to a locked position beneath the bed of the table from which it can be released for further play only upon the deposit of an additional coin.

The balls thus released are admitted one by one to an elevator by means of which the balls are elevated onto a receiver therefor disposed within the aforesaid gate, the receiver being operatively connected to the elevator whereby the receiver is moved into a ball receiving position when the elevator is operated and the receiver is arranged in such a manner as to prevent balls returning to the gate from moving onto the receiver.

Means are provided for manipulating the position of the ball receiver on the bed of the table, thereby to spot the ball pursuant to the performance of a particular pocket or cushion-to-pocket shot which appeals to the fancy of the operator, a spring loaded cue, also manipulatable for this purpose, being provided to impel the ball.

The bed and the pockets of the table are enclosed so as to be inaccessible to the operator. The aforescribed functions of the device, however, are rendered manipulatable externally thereof by the provision of external control means for the ball releasing means, elevator, ball receiver, and cue, as will more clearly appear as the description proceeds.

Still other objects and advantages of the invention not specifically set forth hereinabove are those inherent in or implied from the novel construction, combination and arrangement of parts hereinafter to be described in detail with reference to the accompanying drawings and there-

after claimed, having the above and other objects in view.

In the accompanying drawings, a preferred embodiment of the invention is disclosed which is constructed according to the best mode so far devised for the practical application of the principles of the invention and in which:

Figure 1 is a plan view of a mechanical pool table constructed in accordance with a preferred embodiment of the invention.

Figure 2 is a sectional view of the table taken along the line 2—2 of Figure 1.

Figure 3 is a sectional view taken along the line 3—3 of Figure 2.

Figure 4 is a sectional view taken along the line 4—4 of Figure 2.

Figure 5 is a sectional view as seen along the line 5—5 of Figure 2.

Figure 6 is a plan view of a fragmentary portion of the table shown in Figure 1 in which the elevator and ball receiving and spotting means are shown in greater detail.

Figure 7 is a sectional view taken along the line 7—7 of Figure 6.

Figure 8 is an enlarged sectional view of the coin receiver and levers controlled thereby as viewed substantially along the line 8—8 of Figure 1.

Figure 9 is a plan view of the parts illustrated in Figure 8.

Figure 10 is a sectional view taken along the line 10—10 of Figure 9.

Figure 11 is a sectional view as seen along the line 11—11 of Figure 9, and

Figure 12 is a view partly in plan and partly in section of the coin receiver as viewed substantially along the line 12—12 of Figure 8.

Referring now to the drawings for a more detailed description of the invention, the numeral 15 generally designates a mechanical pool table according to a preferred embodiment of the invention, it being understood that in carrying out the principles thereof many changes may be made in the form, construction, and arrangement of the parts, as will be apparent to those skilled in the art to which the invention appertains.

The table 15 comprises a bed or surface 16 over which the balls are impelled. The bed is surrounded by side walls 17 to which suitable legs 18 for the table are secured, the legs at the operator's end of the table being shorter than the legs at the other end thereof such that the bed is inclined somewhat from the horizontal in order that a ball thereon will be returned to an arcuate gate or opening 19 therein in the event that the

ball fails to pass through any one of a plurality of pocket holes 20 or alley holes 21 formed in the bed 16, the ball being directed to the gate by either one of a pair of diagonally disposed guides 22 which, together with a back stop 23 substantially close the operator's end of the table.

The side walls 17 also support a plurality of pairs of upper and lower members 24, 25 respectively, between each pair of which members a resilient member 26 is secured. The members 26 comprise the cushions of the table and are so spaced as to form pockets 27 therebetween for the holes 20, substantially as shown in Figure 1. A plurality of elongated members or strips 28, each of which carries a cushion member 29 on the tip thereof, are arranged on the bed 16 in such a manner as to form alleys 30 therebetween leading to the holes 21. A barrier 31 also is disposed on and secured to the bed substantially centrally thereof and comprises upper and lower members 32, 33 respectively, between which members a cushion member 34 is secured. Cushion members 26, 29, and 34 may be formed of any resilient material suitable for the purpose such, for example, as felt, rubber, or cork.

A runway or tray 35 is secured to the side walls 17 beneath the bed 16 to receive the balls which pass therethrough by way of gate 19 or holes 20, 21 therein, the runway being tilted from the horizontal and being provided with a plurality of guide strips 36, 37, 38, and 39 which co-operate with small arcuate trays 40, 41 supported on strip 39 and a triangularly shaped, arcuate tray 42 secured to a member 43 depended from the bed 16 to direct the balls to a narrow passageway 44 provided between strips 38 and 39.

A gate 45 is provided for normally closing the entrance to passageway 44 and is carried by a rod 46 which is journalled in strip 39 and a member 47 also secured to runway 35. Rod 46, on the opposite end thereof to gate 45, is formed to provide a crank 48 which carries a pair of connecting rods 49, 50. The opposite ends of connecting rods 49, 50 are respectively secured to a bell crank 51 pivotally supported on member 47 and a forked lever 52 pivotally supported on an upstanding arm 53 rigidly secured to member 47. The other end of bell crank 51 is connected to a rod 54 which is mounted for sliding movement in strip 39 and a member 55 which is also secured to runway 35. The free end of rod 54 serves as a second gate for closing the outlet of passageway 44 when forked lever 52 is moved in the direction of arrow 57 shown in Figure 8. This movement of lever 52 drives crank 48 in the direction of arrow 58, thereby moving gate 45 to the dashed line or open position 59 thereof. This movement of lever 52 also drives bell crank 51 through connecting rods 49, 50 in the direction of arrow 135, thereby moving the free end of rod 54 to the dashed line or closed position 56 thereof.

As illustrated, three balls are admitted into the passageway 44 when lever 52 is moved as described in the foregoing, it being understood that the distance between the gates 45 and 54 may be so arranged as to accommodate one or more balls within the passageway 44, as is desired. Upon return of lever 52 to the initial position thereof, gate 54 is opened and gate 45 is closed, thus placing the balls in the passageway in readiness for use and preventing the admittance of additional balls thereto until lever 52 is again operated as in the foregoing.

Movement of lever 52 is controlled by a coin receiving mechanism generally designated 60 and

supported on a plate 61 disposed within a corner of a framework 62 for covering the top of table 15 and in which a glass cover 63 is mounted whereby access to the bed 16 and the pockets and alleys thereof is prevented but movement of the balls with respect thereto is rendered clearly visible through the glass covering.

Coin receiving mechanism 60 comprises an outer cup-shaped cylinder 64 into which an inner cup-shaped cylinder 65 is telescopically received. Cylinder 64 is provided with a boss or hub 66 having a bore 67 therethrough in which a shaft 68 is journalled. Cylinder 65 is secured to shaft 68 as by a set screw 69, and, accordingly, turns therewith when a lever 70, also carried by the shaft, is operated. Lever 70 extends through a slot 71 in plate 61, thus rendering the lever available for manipulation thereof exteriorly of the table 15.

20 A slot 72 for receiving a coin is provided in cylinder 64, which slot is in registered alignment with a slot 73 of the same diameter provided in cylinder 65 when cylinder 65 is moved into a position in which a stop member 74 carried thereby 25 engages a stop pin 75 carried by cylinder 64. The depth of slot 73 is increased at 76 to receive the flat portion 77 of a trigger lever 78 which is disposed within a cavity 79 formed in cylinder 65 and pivotally supported therein at 80. A coil spring 81 also is disposed within cavity 79 between a wall thereof and the lever 78 such that the end of the lever adjacent the flat portion 77 thereof is yieldably forced well into slot 73, and the other end 82 of the lever is yieldably forced into the 30 path of a stop 83 carried by cylinder 64 such that further movement of cylinder 65 relative to cylinder 64 in the direction of arrow 84, Figure 8, is stopped when lever 78 engages stop 83. In this position of cylinder 65, the same has moved 35 sufficiently to open gate 45 to admit the balls to passageway 44, a pin 85 disposed within the bifurcated portion 86 of forked lever 52 and carried by cylinder 65 being employed to complete the operative connections between gates 45, 54 40 and coin control lever 70. In this position of cylinder 65, however, lever 78 is not accessible from slot 72 and, therefore, cannot be picked, sprung, or otherwise tampered with for the purpose of operating the coin receiver 60 without inserting a coin therein. When a coin of the proper size is inserted in slot 73, however, lever 78 is forced outwardly thereof against the biasing action of spring 81 and the end 82 of lever 78, therefore, clears the stop 83 when cylinder 65 is moved in the direction of arrow 84.

In such case, movement of cylinder 65 continues until stop member 74 carried thereby engages a second stop pin 87 carried by cylinder 64. In this position of cylinder 65, slot 73 and the coin therein are adjacent to an opening 88 provided in cylinder 64 through which the coin is adapted to be ejected from the coin receiver 60. For this purpose, a plunger or rod 89 is slidably disposed within a bore 90 formed in cylinder 65 preferably coaxially with slot 73 therein. A plate 91 is secured to the inner end of rod 89 and a coil spring 92 is disposed thereabout between cylinder 65 and the plate whereby the plate is normally yieldably urged against shaft 68, the top of the rod, when in this position, being flush with the bottom of slot 73 in order to receive the coin therein. As the coin moves adjacent to ejector opening 88 therefor, however, plate 91 engages a pin 93 carried by cylinder 64 whereby plunger 89 is forced against the coin, thereby to eject the

same, the coin then falling to a suitable retainer therefor, not shown. It will be understood that the glass cover may be hinged to the table 15 by means of suitable hinges 94 and may be locked thereto as by suitable latch means 95 and lock 96 therefor whereby the coins collected in the table may be removed therefrom only by a person in possession of a key to the lock.

When rod or gate 54 is withdrawn from passageway 44 as cylinder 65 is returned to the coin receiving position thereof, the leading ball in the passageway abuts against the turned up edge of a leaf spring 97 supported at the opposite end thereof by runway 35 and disposed beneath a ball elevator generally designated 98. Elevator 98 15 may be formed in any manner adapted to force spring 97 down so that one ball may be moved onto the elevator and elevated thereby to a position above bed 16 from which position the ball may thereafter roll upon a ball receiver 99. When 20 the elevator is moved to raise the ball, spring 97 moves up to block the passageway thereby releasing but one ball at a time therefrom.

In the form as illustrated, elevator 98 comprises a tube 100 about which a pair of spaced wires 101, 102 each is wound in a full turn and secured thereto as by solder, the wires being spaced just sufficiently to support a ball therebetween. One end of each wire 101, 102 is bent substantially at right angles and is thereafter doubled back upon itself to join the other end of the wire to which it is secured as by solder, thereby providing a closed V therebetween. The first mentioned end of the wire thereafter is bent to form a U, the bight portion of which forms the seat for the ball entering the elevator and the leg of the U opposite the doubled back portion thereof serves to guide the ball as it rolls therewith to receiver 99. If desired, one or more guides 103 may be mounted on bed 16 to insure that the ball will not move off the elevator laterally thereof.

Elevator 98 is supported on a rod 104 for rotation therewith, the rod being extended through tube 100 and having an arm 105 secured thereto as by a set screw 106, to which arm a wire 107 from elevator 98 is secured. At this point on the elevator, wires 101, 102 are joined as by a wire 108 thereby to provide a fixed spacing therebetween and a rigid structure.

Rod 104 conveniently may be journaled in the table side wall 17 with the end of the rod projecting beyond the wall to receive a control lever 109 for manipulating elevator 98 exteriorly of table 15. A suitable slot or opening 121 is provided in bed 16 through which the elevator 98 is adapted to move as lever 109 is operated.

Rod 104 also supports an idling pulley 110 which is free to rotate thereon. A belt 111 is trained about pulley 110 and also about a driving pulley 112 to which it is secured. Driving pulley 112 is secured to a shaft 113 for rotation therewith, shaft 113 also conveniently being journaled in side wall 17 and being extended outwardly therefrom to receive a knob 114 by manipulation of which the driving pulley may be caused to rotate and move belt 111. Belt 111 is secured to a lever 115 one end of which is pivotally supported on a vertical pivot 116 carried by side wall 17 and the other end of which extends to arcuate gate or slot 19. This end of lever 115 is bent at right angles to enter slot 19, and the sides are bent forward to support a shaft 117 upon which the ball receiver 99 is pivotally supported. Accordingly, movement of knob 114 causes receiver 99 and the ball thereon to assume different positions on bed

16, thus providing means for spotting the ball thereon.

Rod 104 also supports a segmented pulley 118 secured thereto for rotation therewith. A suitable belt or cable 119 is secured to pulley 118 and trained thereover to make connection with a coil spring 120, the other end of which is secured to lever 115. By reason of this arrangement, as control lever 109 is operated to elevate a ball to receiver 99, the receiver is moved into a position to receive the ball as it rolls off of the elevator.

Ball receiver 99 may be formed in any manner adapted to retain a ball thereon, being formed, as illustrated, of a single length of wire, the ends of which are wound about shaft 117 to form a loop 122 depended therefrom and a cup-shaped portion 123 projected forwardly therefrom and comprising the double-backed ends of the wire. A weak spring 124 also is coiled about shaft 117 to bias cup portion 123 upwardly in order to prevent a ball moving toward gate 19 from moving onto receiver 99. The weight of a ball on the receiver 99, however, is sufficient to yieldably overcome the biasing action of spring 124 whereby the ball may be impelled from the receiver in a position thereof substantially flush with the surface of bed 16.

The means for impelling the ball comprises a spring loaded cue generally designated 125. Cue 125 comprises a tube 126 which projects through a suitable opening 127 in side wall 17 arranged to permit lateral swinging movement of the tube about a vertical pivotal support 128 therefor. Pivot 128 preferably is substantially aligned coaxially with pivot 116 in order that cue tip 129 secured to a plunger 130 may be caused to lie adjacent to a ball on receiver 99 as the receiver and cue tip are moved along arcuate opening 19 about their respective pivots 116, 128 in spotting the ball and directing or aiming the cue thereat pursuant to performing a selected shot.

Power for impelling the ball is supplied by a coil spring 131 arranged about plunger 130 between a pin 132 carried thereby and tube 126, power being stored in spring 131 as the same is compressed when plunger 130 is pulled rearwardly by means of a suitable knob 133 secured thereto. Cue tip 129, therefore, strikes the ball under power of spring 131 when knob 133 is released, the force of the blow being determined, in each case, by the extent to which the spring is compressed. A coil spring 134 preferably is arranged about plunger 130 between tube 126 and knob 133 to cushion the forward movement of the plunger, thereby to prevent damage to the cue and support therefor otherwise arising from the impact.

From the foregoing description of the table 15, the operation thereof should now be apparent. Accordingly, a brief description of the operation will suffice.

Coin control lever 70 is pulled all the way back in order to receive a coin of the proper size into slot 73 by way of slot 72 of coin receiver 60. Lever 70 is now moved all the way forward to admit balls to passageway 44 and to prevent the movement of the balls therethrough until lever 70 thereafter is pulled all the way back, as explained in the foregoing.

The balls are now ready to be elevated one by one to the ball receiver 99. This is accomplished by first moving control lever 109 in a clockwise direction to depress spring 97 so that a ball may enter elevator 98. Lever 109 is now rotated counter clockwise to deliver the ball to the receiver

which also moves toward the elevator as lever 109 is rotated because of the connections therebetween.

Knob 114 is now rotated to spot the ball on bed 16 in a selected position thereon to suit the fancy of the operator. Knob 133 is now moved laterally to align the cue tip 129 behind the ball and to aim the cue in the intended line of travel of the ball, the impelling blow being delivered thereto by withdrawing plunger 130 to a desired extent and thereafter releasing it.

It is obvious that various ways of playing different games on the pool table will be suggested to those who operate the device. For example, different scoring values may be assigned to the different pocket holes and to the various alley holes and for various bank shots. Also, different persons may play successive balls rendered available by the insertion of a single coin into the device.

While this invention has been described in particularity with respect to an example thereof which gives satisfactory results, it will be apparent to those skilled in the art to which the invention appertains that the same is susceptible of additional embodiments, variations, and additions without departing from the spirit and scope of the invention as defined by the appended claims.

I claim as my invention:

1. In a mechanical pool table, the combination of a bed inclined from the horizontal, an arcuate gate arranged at the lower end of the bed for passing balls therethrough, means arranged within said gate for supporting a ball thereon in a ball impelling position, pivotally mounted elevating means for moving a ball from a position beneath the bed to a position from which it will be conveyed by gravity from the elevating means directly onto said supporting means, means for yieldably urging said supporting means into a position for preventing a ball from rolling thereupon from the bed, means for moving said supporting means along said arcuate

gate thereby to spot the ball on the bed, and a ball impelling means movable independently of the ball supporting means behind the ball in the spotted position thereof and aimed in an intended line of travel of the ball.

2. In a mechanical pool table, the combination of a bed inclined from the horizontal, a gate arranged at the lower end of the bed for passing balls therethrough, means movably arranged within said gate for supporting a ball thereon in a ball impelling position, pivotally mounted elevating means for moving a ball from a position beneath the bed and for conveying the ball by gravity therefrom directly onto said supporting means, means actuated by the elevating means for moving the ball supporting means into a position to receive the ball from the elevating means and a ball impelling means swingably and slidably movable behind the ball on said supporting means and independently thereof to be aimed in an intended line of travel of the ball.

FELIX RADINSKY.
